UNITED STATES PATENT OFFICE.

RAYMOND A. HEISING, OF MILLBURN, NEW JERSEY, ASSIGNOR TO WESTERN ELECTRIC COMPANY, INCORPORATED, OF NEW YORK, N. Y., A CORPORATION OF NEW YORK.

SIGNALING SYSTEM.

Application filed July 6, 1918, Serial No. 243,566. Renewed June 1, 1922. Serial No. 565,254.

To all whom it may concern:

Be it known that I, RAYMOND A. HEISING, a citizen of the United States, residing at Millburn, in the county of Essex and State 5 of New Jersey, have invented certain new and useful Improvements in Signaling Systems, of which the following is a full, clear, concise, and exact description.

This invention relates to signaling systems, and more particularly to signaling systems of the type in which high frequency oscillations are modulated in accordance with signals.

An object of the invention is to provide a 15 modulating and amplifying arrangement of the vacuum tube type in which the number of necessary current sources may be small.

Another object of the invention is to provide means to enable vacuum tubes arranged 20 in cascade to be supplied from common sources of electrical energy.

A further object of the invention is to provide a circuit connection for a vacuum tube modulator and vacuum tube amplifier 25 which will permit the use of common sources of energy for filament heating, space current and impedance controlling purposes.

Still other features of the invention relate to certain combinations and arrangements of 30 circuits hereinafter described and particularly pointed out in the claims, the advantages of which will be apparent to those skilled in the art.

In the drawing, which represents diagrammatically one arrangement of circuits 35 according to this invention, a source 1 of high frequency oscillations is illustrated in circuit with primary winding 2 of transformer 3 which has a secondary winding 4. Microphone 5, which is merely representative 40 of any form of signal transmitter or of an incoming signal transmitting line, is in circuit with a source of energy 6 and primary winding 7 of transformer 8, the secondary winding 9 of which is in series with winding 4.

A modulator 10, comprising a highly evacuated electron discharge tube having a hot filament cathode 11, a plate electrode or 50 anode 12, and a grid or impedance-varying element 13, has an input circuit connecting its grid and filament including windings 4 and 9 and source 14, which serves to maintain grid 13 at any desired normal negative 55 potential with respect to cathode 11. Shunt-

ed around winding 9 are a variable capacity element 15, which serves as a path for high frequency oscillations, and a high resistance element 16, which serves to stabilize the impedance reaction of the secondary circuit 60 of the transformer upon its primary over the range of voice frequencies, so as to prevent distortion. A capacity element 17 may be employed as a high frequency path shunting the source 14, particularly where the source 65 must be located at a considerable distance from the tube of modulator 10 and may have leads of considerable length subjected to various inductive and reactive disturbances. The output circuit of modulator 10 70 includes a source 18 of space current and a tuned loop circuit 19 comprising variable capacity 20, an inductance 21 and an additional inductance element 22 which may be cut in or out of circuit by switch 23. 75

A high resistance 24 having one terminal connected to the plate 12 through a capacity element 25 and its other terminal connected by variable tap 26 to source 14, serves as an input circuit for an amplifying device 27 80 upon the input terminals of which it impresses the high frequency variations in electromotive force occurring across the output circuit of modulator 10. Amplifier 27 preferably comprises a highly evacuated electron 85 discharge device having a hot filament cathode 28, a plate or anode 29 and a grid or impedance-varying element 30. Filaments 11 and 28 are heated by a common current source 31. 90

The output circuit of amplifier 27 includes a variable primary winding 32 coupled to a variable secondary winding 33 which is connected to line 34 by a variable shunt capacity 35 and a variable series resistance 36, 95 thus enabling circuit 33, 35, 36 to be tuned flatly to the modulated high frequency current to be transmitted. Capacity elements 37, 38 and 39 are provided to serve as high frequency paths for the reason set forth in 100 connection with the description of capacity element 17.

The operation of the system may now be readily understood. High frequency oscillations impressed by the primary winding of 105 transformer 3 upon the input circuit of modulator 10 are modulated in accordance with signal variations impressed upon the secondary of transformer 8. The windings of transformer 3 have low mutual reactance, 110

and since the secondary of transformer 8 is shunted by high frequency path 15, the transformers may be made to have little or no direct action as modulating devices. The distributed capacity of the secondary winding of transformer 8 also serves as a shunt path for high frequency oscillations, and in some instances may enable element 15 to be eliminated. The modulator 10 and amplifier 27 are arranged to be supplied with space current by common source 18, and with filament heating current by common source 31. Source 14 serves to maintain the grids of the modulator and amplifier at the proper normal potentials with respect to their cathodes. The output circuit of modulator 10 will have superposed upon its normal space current amplified variations of speech frequency and the modulated carrier frequency. Circuit 19 is tuned to the carrier frequency and accordingly offers a high impedance to that component while offering a low impedance to speech frequency variations, the effect of the low impedance path being to increase the modulating efficiency of the modulator. The modulated carrier variations impressed across the terminals of resistance 24 and consequently upon the input circuit of amplifier 27 are, after amplification, impressed by the output circuit of amplifier 27 upon line 34.

It will be apparent to those skilled in the art that this invention may be applied to other systems of signaling as well as to teletphony and to guided carrier wave systems.

It is to be understood that the specific signaling system herein shown and described is merely illustrative of one form in which this invention may be embodied, and that the relative arrangement and location of elements may be materially varied from that set forth.

What is claimed is:

1. In combination, two electron discharge devices each having a cathode and input and output circuits connected thereto, common means for rendering said cathodes active, common sources of electromotive force in said input and output circuits, and an element of high impedance forming part of the output circuit alternating current path of the first of said devices and also forming part of the input circuit alternating current path of the second of said devices whereby energy variations in the output circuit of the first of said devices are impressed upon the input circuit of the second of said devices.

2. A plurality of electron discharge devices each having a cathode, an anode and a control element, common means for heating said cathodes and for supplying electron discharge currents in said devices, a common source of potential between said cathodes and their respective control elements

and a path of high impedance to currents of the frequencies which it is desired to transmit but of lower impedance for currents of materially differing frequencies common to the cathode anode circuit of one of the 70 devices and the cathode control element circuit of another of said devices whereby said electron discharge devices are connected to operate in tandem.

3. The combination of two electron discharge devices each having a cathode, an anode and an impedance control element, common means for maintaining said cathodes in electron emitting condition, common means for supplying electron discharge current for said devices, a common source of potential difference between said cathodes and their respective control elements, and an element of high resistance common to the cathode anode circuit of one of said 80 devices and the cathode control element circuit of the other of said electron discharge devices whereby the first device may operate to vary the impedance of the second device.

4. The combination of a plurality of vacuum tube discharge devices arranged in tandem, said devices each having a hot filament cathode, an anode and an impedance varying element, a common source of heating current for said filaments, a common source of space current for said discharge devices, common means for determining the normal potential of each impedance varying element with respect to its associated cathode, and a closed loop circuit tuned approximately to the mean frequency of the currents to be transmitted common to a cathode anode path of one of said devices and a cathode impedance element path of 100 another of said devices.

5. In combination, a vacuum tube modulator and a vacuum tube amplifier each having a hot cathode and input and output circuits connected thereto, common means for 110 heating said cathodes and a common source of electromotive force for said output and said input circuits, and means connecting said modulator and amplifier in tandem.

6. In combination, a modulator and an 115 amplifier each comprising a highly evacuated container having a hot filament cathode, an anode and a control electrode, a common source of space current, and a common source of input circuit potential for said 120 modulator and amplifier.

7. A modulator having an input circuit and an output circuit, means connected to said input circuit to impress carrier waves and modulating waves thereupon, and a 125 path including a loop tuned to said carrier frequency shunted across said output circuit.

8. A modulator having an input circuit and an output circuit, a source of carrier 130

waves, means to impress carrier waves from said source together with modulating waves upon said input circuit, a shunt circuit connected across said output circuit including 5 inductance and capacity, said shunt circuit being of relatively low impedance to one of said waves while being of high impedance to the other of said waves.

9. A modulator having an input circuit 10 and an output circuit, a source of carrier waves, means to impress carrier waves from said source together with modulating waves upon said input circuit, and a path including capacity and inductance shunted across 15 said output circuit and tuned to the frequency of one of said waves.

10. A modulator having an input circuit and an output circuit, means to impress car-

rier waves and modulating waves upon said input circuit, and means connected in shunt 20 to said output circuit including a loop tuned to the frequency of one of said waves.

11. A modulator having an input circuit and an output circuit, a source of carrier waves, means to impress carrier waves from 25 said source together with modulating waves upon said input circuit, and means connected in shunt to said output circuit including inductance and capacity, said means being of relatively low impedance to said 30 modulating waves while being of high impedance to carrier waves.

In witness whereof, I hereunto subscribe my name this 1st day of July A. D., 1918.

RAYMOND A. HEISING.
